TO STANDARD-KNAPP CORPORATION, A CORPORATION OF NEW YORK

PASTE APPLYING MECHANISM

Application filed April 15, 1929. Serial No. 355,084.

The present invention relates to labelling machines and has for an object to provide an improved paste applying mechanism. The invention has been developed in connection with the construction of a machine for applying labels to cans and for convenience of disclosure such an embodiment of the invention will be more particularly described to illustrate the principles of the invention. In 10 the machine to be described cans are rolled along a runway and a label is wrapped around each can, its ends being overlapped and secured by adhesive.

The present invention provides an improved positively acting device for applying the adhesive to the ends of the labels, the feed of the adhesive being controlled by the passing of the cans to insure the feeding of a quantity of adhesive proportioned to the 20 number of labels applied.

The nature and objects of the invention will be better understood from a description of a particular embodiment thereof for the purpose of which description reference 25 should be had to the accompanying drawings forming a part hereof and in which—

Figure 1 is a plan view of a portion of a can labelling apparatus with a paste applying mechanism constructed in accordance 30 with the invention applied thereto,

Figure 2 is a side view of the paste applying mechanism,

Figure 3 is a sectional view taken on the line III—III of Fig. 2,

Figure 4 is a top plan view,

Figure 5 is a plan view partly in section of the nozzle by which the adhesive is applied, and

Figure 6 is a detail central sectional view 40 taken on the line VI—VI of Fig. 5.

The apparatus shown comprises ways 5, 5 preferably adjustable toward and from each other to fit cans of different lengths which are rolled therealong to receive labels from 45 a stack of labels 6, shown in dot and dash lines. In operation the cans 7, indicated in dot and dash lines, are rolled along the conventionally indicated ways 5 from left to right in Fig. 1 as by conveyor elements conventionally indicated at 8, each can being

previously provided with a sufficient quantity of adhesive so that as it rolls over the stack of labels, the top label will be picked up by the adhesive. As the can passes forward the label will be completely wrapped around the can and its ends overlapped. The present invention is concerned with the improved apparatus for applying adhesive to the overlapping end of the label in such position that when the label is wrapped completely around the can its ends will be firmly secured in the overlapping relation.

As shown, the improved apparatus comprises a nozzle 10, which is supplied with adhesive from an adhesive container 11 through a connecting conduit 12. As best shown in Figures 1 and 4 the container 11 and associated parts are adjustably mounted on the frame so that the position of the nozzle 10 may be varied in accordance with the length of the labels used. For this purpose the supporting extension 110 for the container is made slidable along the guideways 111 of the frame of the machine. The adhesive is fed positively by a gear pump 15 which is intermittently actuated under control of the cans moving on the ways, provision being made for manually adjusting the amount of adhesive caused to be fed by each can. The shaft 16 carrying one of the gears of the gear pump extends diametrically through the adhesive container and on its projecting end carries a ratchet 17 actuated by a pawl 18 on the rocking arm 19. The arm 19 is actuated by a cam 20 on a constantly rotated shaft 21, said cam engaging a roller 22 on the lower end of the arm 19. The extent and timing of the operation of the arm 19 to actuate the adhesive pump is controlled through an adjustable mechanism which is actuated by a lever 25 pivoted at 26 on one of the ways 5 in position to be engaged by each passing can.

The operative connection between the can engaging lever 25 and the pump operating lever 19 comprises a detent rod 28 connected at 29 to the lever 19 and urged toward the left in Fig. 2 by a spring 30 to move the roller 22 into engagement with the cam 20. The movement of the rod to the left is limited by

an adjustable stop 31 arranged to be positioned in any one of the holes 32 to permit a greater or less extent of movement of the lever 19 by the cam 20 each time that the 5 roller is engaged by the cam. The detent rod 28 is held in retracted position toward the right in Fig. 2 by a pawl 33 engaging a notch 34, Fig. 4, said pawl being spring pressed toward rod retaining position by the 10 spring 35. The pawl 33 is arranged to be tripped to release the rod 28 each time a can engages the lever 25, the tripping connection comprising a slotted link 36 arranged to be connected to the arm 37 by clamp screw 38. 15 In operation the cam 20 engages the roller 22 to rock the lever 19 thus rotating the ratchet wheel 17. As the rod 28 moves to the right in Fig. 2 during the actuating movement of the lever 19, the pawl 33 will engage the notch 34 to retain the rod in this 20 retracted position. If for a time no can passes along the runway, the pump will not be operated but if a passing can actuates the lever 25 the pawl 33 will be released and the 25 rod 28 will move to such an extent as it is permitted by the adjustable pin 31 to permit the corresponding amount of actuation of the lever 19 by the cam 20 upon its next revolution. 30 The construction of the nozzle is indicated in Figs. 5 and 6. The nozzle shown is made in two sections 40, 41 formed with a paste feeding slot 42 and suitable means are provided for assuring a substantially even flow 35 of paste throughout the length of this slot. For the purposes of distribution obstructions 43, 44, 45 are formed within the nozzle which serve both as spacers to hold the two parts of the nozzle suitably spaced and as guides to 40 distribute the flow of paste along the length of the slot. The two sections are held rigidly together by screws 46.

In order that the length of the strip of paste fed may correspond to the width of the 45 label, slides 47 are arranged in the slot adjustable along the length thereof to close the outer end of the slot beyond the width of the label. These slides extend outwardly at the two sides 50 of the nozzle and are formed with suitable handles 48 for convenient operation. When the slides are adjusted, they may be clamped in adjusted position by means of nuts 49 screwing onto the tapered ends of the nozzle sections 50.

55 The foregoing particular description is illustrative merely and is not intended as defining the limits of the invention.

We claim:

1. A label applying apparatus comprising 60 a label support, a conveyor for carrying articles successively past said label support, an adhesive container, a nozzle connected to the adhesive container and overlying the label support to apply adhesive to labels on said support across substantially the entire 65

end thereof, a positively acting pump for feeding adhesive from the adhesive container to the nozzle and a tripping mechanism actuated by each article carried by the conveyor for controlling the actuation of the 70 pump.

2. A label applying apparatus comprising a label support, an adhesive container, a nozzle connected to the adhesive container and overlying the label support to apply adhesive 75 to labels on said support, a positively acting pump for feeding adhesive from the container to the nozzle and means for actuating the pump comprising a stop member engaged and actuated by each article to which a label is 80 to be applied, and means manually adjustable to determine the extent of each actuation.

3. A label applying apparatus comprising can-ways for articles to which labels are to be applied, means for continuously moving the articles along said can-ways, a label support beneath said can-ways, means for applying labels to successive articles carried by the 85 can-ways, an adhesive container, a nozzle connected to said container arranged to apply adhesive across one end of each successive label, and a positively acting feed mechanism controlled by articles carried by the can-ways 90 for feeding adhesive from the adhesive container to the nozzle.

4. A label applying apparatus comprising a support for a stack of labels, can-ways for guiding cans over the stack of labels to receive labels therefrom, means for continuously moving the cans along said can-ways 100 an adhesive container, a nozzle having a discharge slot positioned to apply adhesive to the top label of the stack along a line adjacent one edge thereof and means controlled by the cans passing a given point on the ways for feeding adhesive to the nozzle in an amount proportioned to the number of cans passing said point.

5. A label applying apparatus comprising a support for a stack of labels, can-ways for guiding cans over the stack of labels to receive labels therefrom, an adhesive container, a nozzle having a discharge slot positioned to apply adhesive to the top label of the stack along a line adjacent one edge thereof, a 110 pump for feeding adhesive from the container to the nozzle, means connecting said pump with a source of power and mechanism tripped by each passing can to render said 115 means effective.

6. In a label applying apparatus means for supporting a stack of labels, means for conveying cans successively across the top of said labels, each can being adapted to pick up a label in transit thereover, a nozzle adapted to apply adhesive across one end of each label, positive means for forcing adhesive through said nozzle, and means engaged 120 by each can subsequent to picking up a label 125

for controlling the operation of said positive means.

7. In a label applying apparatus means for supporting a stack of labels, means for conveying cans successively across said stack of labels to receive labels therefrom, a nozzle adapted to apply adhesive across one end of each label as they are removed from the stack, positive means for forcing adhesive 10 through said nozzle, said nozzle having an elongated discharge outlet, adjustable means for varying the extent of said outlet, and means engaged by said cans in transit for controlling the operation of said positive 15 means.

8. In a device of the character described, a supporting structure, a paste receptacle adjustably mounted on said structure, tracks on said structure, label-holding means between 20 said tracks, means for discharging paste from said receptacle to labels, pump means for conveying material from said paste receptacle to said second-mentioned means, and means operable by movement of a container 25 through said device to control the actuation of said pump.

9. A labeling device, including means operable by movement of a receptacle therethrough for controlling the discharge of 30 paste material to a label, said means including a pump and a lever actuated by movement of the receptacle to control actuation of said pump.

In testimony whereof, I have signed my 35 name to this specification this 9th day of April, 1929.

GORDON C. COOKE.
